COMBINED CULINARY SCRAPER AND SIFTER

Florence L. Hoberg, P.O. Box 1105,
Eugene, Oreg. 97401

Filed Mar. 25, 1968, Ser. No. 11,116

Term of patent 14 years

Int. Cl. D7—02

U.S. Cl. D44—29

I claim:

The ornamental design for a combined culinary scraper and sifter, substantially as shown and described.
